(57) **CLAIM**

The ornamental design for a dough roller, as shown and described.

DESCRIPTION

FIG. 1 is a perspective view of a first embodiment of the inventive design for a dough roller;

FIG. 2 is a side elevational view of the design of FIG. 1;

FIG. 3 is an opposite side elevational view of the design of FIG. 1;

FIG. 4 is a top plan view of the design of FIG. 1;

FIG. 5 is a bottom plan view of the design of FIG. 1;

FIG. 6 is an end elevational view of the design of FIG. 1;

FIG. 7 is an opposite end elevational view of the design of FIG. 1;

FIG. 8 is a bottom plan elevational view of the design of FIG. 1, absent a removable component;

FIG. 9 is a perspective view of the removable component of the dough roller, shown separately for clarity of illustration;

FIG. 10 is a side elevational view of the inventive design of FIG. 9;

FIG. 11 is a top plan view of the design of FIG. 9;

FIG. 12 is a bottom plan view of the design of FIG. 9;

FIG. 13 is an end elevational view of the design of FIG. 9; and,

FIG. 14 is an opposite end elevational view of the design of FIG. 9.
